FURNITURE PULL

Melbourne F. Smith, Jr., Lenoir, N.C., assignor to Broyhill Furniture Factories, Lenoir, N.C., a partnership

Filed Jan. 15, 1964, Ser. No. 78,212

Term of patent 14 years

(Cl. D10—8)

FIG-1

FIG-2

FIG-3

FIG-4

FIGURE 1 is a perspective view of a furniture pull showing my new design;

FIGURE 2 is a front elevational view thereof;

FIGURE 3 is a top plan view thereof; and

FIGURE 4 is a side elevational view thereof.

The back of the furniture pull is substantially plain and unornamented.

I claim:

The ornamental design for a furniture pull, substantially as shown and described.
